MIDDINGS PURIFIER

Creighton H. Morrison, Minneapolis, Minn., assignor to General Mills, Inc., a corporation of Delaware

Application August 12, 1949, Serial No. 109,886

23. Claims. (Cl. 209—129)

1

The present application relates to electrostatic separation and more particularly to an improved apparatus for electrostatic separation of cereal stocks.

Electrostatic separators have been proposed in the past in which the stock to be separated is fed downwardly along a smooth inclined plate beneath an upper electrode of the "Venetian blind" type. Such an upper electrode includes a series of transverse strips which are spaced slightly from each other to provide openings through which the attracted particles may pass to the upper surface of the electrodes. These strips are inclined at an angle which feeds the attracted particles downwardly from one strip to the next on the upper surfaces of the strips under the influence of gravity.

With these constructions of the prior art, two separations have been possible. One group of particles may be attracted through the spaces between the strips of the upper electrode and removed separately as they are fed down the upper surfaces of the strips. The remaining particles continue to pass down the lower inclined plate to a point of removal. As far as I am aware, such devices have not been applied successfully to the separation of materials in which both particles to be segregated are "non-conductors." Furthermore, such devices have not permitted precise and accurate separations on a commercial scale.

With these defects of the prior art in view, it is accordingly one object of the present invention to provide an improved electrostatic separator of the inclined parallel electrode type.

It is a further object to provide an electrostatic separator of this type in which the upper electrode is provided with openings or perforations and in which a three-fold separation is made possible.

Another object is the provision of an electrostatic separator of this general type in which the lower or supporting electrode is of novel and improved construction.

Still another object of the invention is the provision of such a separator in which the inclined supporting or conveying electrode is provided with a series of transversely extending steps or corrugations.

A further object is the provision of an electrostatic separator of this general type in which a corrugated or stair step supporting electrode is combined with a perforated or "Venetian blind" type of upper electrode and in which the electrodes are subjected to vibratory action during the feeding of the material between them.

2

Other objects and advantages will be apparent from the following specification, in which a preferred embodiment of the invention has been described with particular reference to the accompanying drawings.

In these drawings, wherein like reference characters indicate like parts,

Fig. 1 is a partial perspective view of an electrostatic separator embodying features of the present invention.

Fig. 2 is a sectional view on the line 2—2 of Fig. 1.

Fig. 3 is an enlarged sectional view similar to Fig. 2 showing details of the electrode construction.

Fig. 4 is a side elevation, partly in section, of another embodiment of the present invention.

Fig. 5 is a front view of the device of Fig. 4, and

Fig. 6 is a partial sectional view showing details of the electrode construction.

The separator includes a base 10, at one end of which is mounted a vertical supporting wall 12. A bracket 14 at the top of the supporting wall 12 includes supporting arms 16 on which a hopper designated generally at 18 is mounted. As shown in Fig. 2, the bottom wall 20 of hopper 18 is inclined downwardly away from the wall 12 and terminates in a transverse feeding edge 22 from which the material in the hopper can be dropped to the space between the electrodes. The front wall 24 of the feed hopper 18 carries at its upper edge a supporting bracket 26. Threaded rods 28 pass through the supporting bracket 26 and are attached to a movable plate 30 serving as a feed gate for the hopper. Nuts 32 on threaded supports 28 permit vertical adjustment of the feed plate 30 so that its lower edge 34 may be accurately positioned at a predetermined distance away from the bottom plate 20 of hopper 18 to obtain the desired uniform rate of feed of the material from the hopper.

In order to assist uniform feeding of the material from the hopper, a vibrator designated generally at 36 is mounted on a bracket 38 fastened to the rear wall 12 of the separator. This vibrator 36 is of any desired known type and generally includes an electromagnet 40 which cooperates with an armature 42 fastened at 44 to the bottom plate 20 of hopper 18. Wires 46 and 48, connected to a suitable power source, rapidly energize and deenergize the electromagnet 40 which alternately attracts and repels the armature 42 so as to vibrate the plate 20 in the desired manner. Any other desired mechanism for op-

taining uniformity of feed from the hopper 18 may be utilized in place of the vibrator 36.

The material to be separated is deposited uniformly from the feed lip 22 of hopper 18 onto the lower electrode 50 of a pair of parallel inclined electrodes. Above the electrode 50 is an upper electrode 52 which is spaced from the lower electrode a distance which is relatively small as compared to the length of the electrodes in the direction of feed. Thus the material deposited on the lower electrode 50 will move downwardly along the length of this electrode and will thus pass through the electrostatic field which is established between the electrodes.

The two electrodes 50 and 52, which are metallic, are mounted on insulating side plates 54 and 56 respectively, which in this particular case are made of transparent plastic material in order that the action of the electrostatic field on the material to be separated may be more readily observed. Side plates 54 and 56 are carried by a horizontal supporting plate 57. The lower metallic electrode 50 includes a metallic rear supporting wall 58 and metallic supporting side walls 60. Side walls 60 are fastened by bolts 62 to the insulating side supports 54 and 56. One of the bolts 62 is connected by a suitable wire 64 to the desired potential source, in this case to ground.

The upper electrode 52 is provided with metallic side flanges 66 which have longitudinal slots 68 therein. Bolts 70 pass through the slots 68 in the electrode flanges 66 and also through slots 72 in the insulating side supports 54 and 56. Slots 72 are substantially perpendicular to the plane of the electrode and also to the slots 68. This combination of perpendicular slots in the electrode flange 66 and side supporting plates 54 and 56 therefore permits adjustment of the upper electrode both toward and away from the lower electrode plate 50, in order to vary the spacing between the electrodes, and also in a direction longitudinally of the electrodes or parallel to the direction of feed. A wire 14 is connected at one end to one of the bolts 70 and at its other end to a suitable direct current high voltage source in order to apply the desired potential to the upper electrode. The difference in potential between the electrodes accordingly establishes an electrostatic field between electrodes 50 and 52 of a strength which depends on the difference in potential and on the relative separation of the members.

The specific construction of the electrodes is shown best in Figs. 2 and 3. The upper electrode 52 includes a series of transversely extending strips 76 which are inclined downwardly in the direction of feed and which are staggered so as to leave openings between them somewhat in the nature of a Venetian blind. Strips 76 may include a substantially vertical rear wall section or riser 78 leaving openings 80 between the upper edge 82 of the vertical wall portion and the extreme lower edge 84 of the transverse strip 76 which is immediately above the vertical wall portion 78. Thus the openings 80 permit the passage of particles of material which are attracted from the lower electrode 50 and which can therefore be removed from the electrostatic field between the electrodes and conveyed downwardly on the upper surface of the inclined transverse strips 76 as shown particularly in Fig. 3.

Because of the staggered or overlapping arrangement of the transverse strips 76 it is apparent that the field near the upper electrode 52

will not be absolutely uniform as it would be in the case of a flat plate parallel to the lower electrode. Instead, the field will be concentrated somewhat at points 86 where the upper edge of each transverse strip 76 meets the vertical rear wall or riser 78.

In previous electrostatic separators of this inclined "Venetian blind" type, the lower or supporting electrode 50 has been in the form of a flat inclined plate. According to the present invention, the lower electrode 50 is provided with a series of steps or corrugations. These steps include the downwardly inclined conveying portions 88 which may be substantially parallel to the transverse strips 76 of the upper electrode and are inclined downwardly to promote the flow of the material down the lower electrode 50. The successive conveying steps 88 are separated by risers 90 which are substantially perpendicular to the step portions 88. The lower portion of each riser 90 meets the step portion 88 which is below it, at a line of intersection 92, and also meets the step portion 88 of the step above it along a line of intersection 94. While this lower stair step electrode 50 is substantially parallel to the upper electrode, it will be apparent that the steps or corrugations will not establish an absolutely uniform field between the upper and lower electrodes. Instead, the field adjacent the lower electrode will tend to be concentrated at the end 94 of each step.

At the end of the lowermost or bottom step 88, the electrode 50 has an extension projecting downwardly and rearwardly as shown at 96, in a direction which in this case is substantially perpendicular to the general plane of the electrode itself. Thus a discharge edge 98 is provided at the end of the bottom step.

It should be noted that the upper electrode 40 extends beyond the discharge edge 98 of the lower electrode in the direction of feed of the material. The electrostatic field between this final discharge edge 98 and the upper edge 86 of the last transverse step 76 is the last of a series of relatively intense electrostatic fields through which the material passes at the edge of each successive step. Since the extension 96 of lower electrode 50 diverges from the final step 76 of the upper electrode 52 beyond the discharge edge 98, the electrostatic field between the upper and lower electrodes will decrease in intensity beyond this point. The field will also tend to be more nearly horizontal, due to the different angular orientation of the extension 96, rather than perpendicular to the general plane of the electrodes 50 and 52 as is the case throughout the remainder of the field.

At the lower end of the electrodes 50 and 52 suitable dividers and conveying chutes are provided to remove the material which is separated by the machine. A collecting plate 100 is mounted at a rather sharp incline below the discharge edge 98 of the lower electrode. This collecting plate 100 is fastened to a conveying chute 102 at 104. The material received by the plate 100 and chute 102 is deposited in a suitable receptacle 106. For convenience an ordinary boxlike receptacle has been shown, although it will be understood that this receiving receptacle 106 could also be the hopper of a subsequent separating unit or could be a suitable chute for feeding material in the desired manner and direction.

An intermediate dividing plate 108, which may be made of insulating material, extends into the edge of the diverging electrostatic field between

the portion 96 of lower electrode 50 and the last transverse upper electrode strip 76. Plate 108 is mounted on a chute 110 which is rigidly connected to a horizontal transverse shaft 112. Shaft 112 is rotatably mounted in bearings 114 on an auxiliary frame 116 mounted on the base 10 of the machine. As shown in Fig. 1, the shaft 112 is provided at its outer end with an adjusting arm 118. A bolt 120 passes through the locking arm and through an arcuate slot 124 in a flange 126 on auxiliary frame 116. A suitable lock nut 122 on the locking bolt 120 may be tightened to retain the adjusting arm 118 in any desired position along the extent of the arcuate slot 124. Thus the chute member 110 and divider plate 108 may be rotated by means of shaft 112 to adjust their position at the lower edge of the electrostatic field. Counterclockwise rotation of shaft 112, as seen in Fig. 2, will lower the divider 108 toward the collecting plate 100, while clockwise rotation of shaft 112 will shift the divider 108 upwardly to a point near the plane of the upper electrode.

To permit lengthwise adjustment of the divider 108, the member is mounted on an intermediate plate 128. This intermediate plate 128 is connected to chute 110 by bolts 130. These bolts pass through longitudinal slots 132 in the intermediate plate 128. Thus the bolts 130 may be loosened and the plate 128 with divider 108 adjusted longitudinally of chute 110 to any desired position.

The material segregated by divider 108 will pass down along the top of the divider and onto chute 110 and will be deposited by the chute in a receptacle 134 similar to receptacle 106. The edge of divider 108 should not project too far into the electrostatic field, in order that the orientation and gradually decreasing intensity of the field will not be influenced adversely by charges which may build up on the divider after contact with the charged particles. Thus the divider remains substantially at the edge of the field. A metallic divider may also be used, in order to minimize the accumulation of charges from the material.

Finally, an insulated collecting plate 136 is mounted just below the final discharge edge of the last strip 76 of the upper electrode 52. Insulating collecting strip 136 is mounted on a chute 138 having a discharge spout 140 to direct the material into a third receptacle 142.

As a result of this arrangement the particles of material which are attracted through the upper electrode and which pass downwardly on the upper surface of the upper electrode will be collected in receptacle 142. At the same time, the material which remains within the electrostatic field between the upper and lower electrodes will be discharged at the lower end of the electrostatic field and will be collected in receptacles 106 and 134. Receptacle 106 will receive that portion of the material which drops substantially directly and vertically from the discharge edge 98 of the lower electrode, while receptacle 134 will receive an intermediate fraction of material depending on the longitudinal and perpendicular or angular adjustment of the divider plate 108 as discussed below.

In order to assist the feeding of the material downwardly along the lower stair step electrode 50, the supporting plate 57 on which the side supports 54 and 56 and electrodes 50 and 52 are mounted are preferably vibrated or reciprocated. In the form shown in Fig. 2, supporting plate 57

is supported on inclined springs 144 and 146. The springs are mounted on the base 148 of a suitable vibrator unit which is fastened to the lower support 10 of the separator by bolts 150. An electromagnet 152 is mounted on the supporting base 148, while a magnetic armature 154 is fastened to one of the supporting springs 146 at 156. The magnet is energized by means of wires 158 and 160 connected to a power source so that the armature 154 is reciprocated at a rapid rate. A rapid vibratory action will accordingly be given to the support 57 and to the electrodes 50 and 52 which are mounted thereon. In the present case, this rapid vibration is in a direction having components both perpendicular to and parallel to the general plane of electrodes 50 and 52. I have also found, as discussed below, that satisfactory results may be obtained by a rapid vibration or reciprocation in a direction parallel to the edges of the steps 38 of lower electrode 50, i. e., a direction transversely of the electrostatic field, parallel to the plane of the electrodes, and perpendicular to the direction of feeding of the material.

With respect to the operation of the present machine, excellent results have been obtained by the use of the magnetic vibrators with a 60 cycle alternating current source which gives a frequency of vibration of 3600 cycles per minute. With the lower plate grounded, a negative potential of from 1500 to 3000 volts may be used for the purification of comminuted wheat stock when the upper and lower electrodes are spaced from one-half to one inch. In other words, a potential difference of between 1500 and 6000 volts per inch of separation is preferred. In this device, the steps of the individual electrodes are inclined downwardly at about $7\frac{1}{2}^{\circ}$ below the horizontal. This angle is substantially less than the angle of repose of the material. The electrodes as a whole are inclined approximately 30° below the horizontal.

In Figs. 4, 5, and 6, another embodiment of the present invention has been shown. In this embodiment, two pairs of electrodes according to the invention are superimposed in a single frame which is vibrated in the manner described below. The device includes a stationary main frame including bottom frame members 174, side frame members 176, and top frame members 178. Within this stationary frame the movable separating unit is mounted. The separator includes side plates 180 and 182 which are connected by cross braces 184. Side plate 180 is suspended from the upper frame member 178 by resilient straps 186 which in this case are metallic. Similarly, side frame 182 is suspended from top frame members 178 by spring straps 188. These straps are oriented as shown in Figs. 4 and 5 so that the frame members 180, 182, 184 may move or reciprocate in a direction substantially perpendicular to the plane of the paper in Fig. 4, i. e., substantially laterally in the plane of the paper in Fig. 5.

Supported by the frame members 180 and 182, 65 is a hopper 190 at the upper rear portion of the device. Hopper 190 may be supplied from a suitable feed chute (not shown) which may be connected to the hopper by a flexible conveyor section in known manner. A feed gate 192 in the hopper may be set to control the rate of feed of the material to be separated from the lower end of the hopper.

This material is fed onto the lower electrode 194 of a pair of parallel inclined electrodes. The upper electrode 196 includes spaced overlapping

strips of the type previously described, while the lower electrode 194 includes steps or corrugations as already outlined.

The material which is projected through the upper electrode 196 and conveyed downwardly on its upper surface is received by a collecting plate 198 and directed into a suitable receptacle or feed chute 200. A fixed receptacle has been shown, for convenience, although a flexible spout is normally employed in a commercial installation to feed the separated material to the next apparatus in the mill flow.

The material which remains in the field between electrodes 194 and 196 is separated into two cuts or flows by the divider edge 202. The material which passes above divider 202 is carried by a collecting plate or chute 204 into a collecting receptacle or further feed chute 206. The material which does not pass above the divider 202 but drops relatively directly from the lower electrode 194 is carried by an inclined feed chute 208 to a second pair of electrode plates arranged on the frame members 180 and 182 below the first pair of electrodes. The second pair of electrodes includes a bottom electrode 210 and an upper electrode 212 of construction similar to the electrodes 194 and 196. Here again a collecting plate 214 receives the material which has been projected through the upper electrode 212 and directs that material into a collecting receptacle or further feed chute 216. A divider 218 separates the material leaving the lower electrode 210 into two fractions. The upper fraction is directed by collecting plate 220 into receptacle 222, while the lower fraction is directed by chute 224 into a further receptacle or chute 226.

With this device, the material which is fed from hopper 190 will ultimately be divided into five cuts or fractions collected at the receptacles 200, 206, 216, 222, and 226 respectively.

As already indicated, the resilient supports 186 and 188 permit vibration or reciprocation of the separating unit, including both sets of electrodes 194, 196, and 210, 212, in a direction substantially indicated by arrow 228 of Fig. 5. While any desired mechanism may be used to obtain the desired rapid vibratory reciprocation, Fig. 5 shows a supporting bracket 230 on side plate 182, and a drive of the so-called "Shaler" type, designated as 232, mounted on bracket 230. In general this drive is of the double eccentric type and includes two rotating unbalanced members 234 and 236, having their weighted portions 235 and 237 directly above each other at all times. The members 234 and 236 are rotated in opposite directions by suitable gearing. In this unit the arrangement of the weights is such that the vertical components of force exerted by one weight exactly counterbalance the vertical components exerted by the other. The resultant force exerted by the counter-rotating weights will be horizontal and will result in reciprocation of the separator unit back and forth in the direction of arrow 228. Such units are well known and need not be described further.

The unbalanced weight vibratory unit is driven by suitable belting 238 from an intermediate pulley 240, which in turn is connected by a belt 242 to a motor or other power source 244. Motor 244 is mounted on a cross member 246 supported by the side frame members 176.

In this embodiment of the invention it will be noted that the direction of reciprocation or vibration is substantially parallel to the edges of the steps in the electrodes. As indicated in Fig. 6,

these electrodes are substantially similar to those of the embodiment previously described. Thus the upper electrode 196 includes spaced transverse strips 248 which are inclined downwardly to feed the material from one step to the next lower step. Each step has a riser or upwardly extending lip 250, the upper edge of which is spaced slightly below the end of the step above so as to leave an opening 252 between each pair of steps 248. The desired fraction of material carried by the lower electrode can then be projected through the openings 252 by application of a suitable potential difference to the electrodes.

Lower electrode 194 includes conveying step portions 256 separated by perpendicular risers 258. In this embodiment of the invention the risers of the lower electrode and the steps of the upper electrode are arranged in substantially one to one ratio so that for a given length of electrode, the same number of steps will be present in the upper electrode as in the lower one. This arrangement contributes a somewhat more uniform field than the construction shown in the previous embodiment in which the steps of the lower electrode were substantially shorter than those of the upper electrode. In this device the total length of one pair of the inclined electrodes is substantially eighteen inches in the direction of feed, with approximately twenty steps per foot. The individual steps are each five-eighths of an inch wide, with a riser or perpendicular distance between steps of one-fourth of an inch. The perpendicular distance between electrodes is one-half inch. With a total electrode width of twenty-four inches, the machine can handle approximately six hundred pounds of stock per hour.

In this case the general plane of the electrodes is inclined at an angle of 30° to 35° below the horizontal, while the individual steps of the electrodes are inclined downwardly at 5° to 10°.

Operation of the device of Figs. 4 through 6 is similar in principle to that of the previous embodiment. The electrodes are connected, as shown schematically in the drawing, so as to establish an electrostatic field between them of the desired intensity. In the connections shown, the same potential difference is applied to each pair of electrodes. Separate connections could be utilized to establish fields of different intensities at the respective electrode pairs.

As indicated in the introductory portions of this specification, "Venetian blind" upper electrodes have been used previously in combination with a lower inclined smooth plate electrode. Such devices have at best given a twofold separation, some of the particles being attracted through the upper electrode and carried downwardly on the upper surfaces of the transverse strips of the upper electrode, while the remaining material is discharged from the lower electrode. Corrugations have also been used in certain other electrode arrangements.

According to the present invention, however, the particular arrangement of the lower electrode, when combined with this upper electrode, has been found to give a surprising additional separation or third cut at the end of the electrostatic field. In the case of comminuted wheat stock, which contains pure bran particles, pure endosperm particles, and particles in which both bran and endosperm are attached in varying proportions, a relatively branney fraction may be attracted through the upper electrode and separated by means of receptacle 142. The remain-

ing stock is conveyed downwardly along the edge of the lower electrode and is subjected to the vibrations imparted to this electrode. The combination of the steps or corrugations and the vibratory action appears to cause some stratification of the material so that relatively large particles of pure endosperm tend to hug the steps rather closely as indicated by the clear circles in Fig. 3. The pure bran particles tend to reach the top of the layer between the electrodes where they pass over the edges 94 of the steps at repeated intervals and are thus ready to be attracted when they are subjected intermittently to the more intense electrostatic field at these points. One of these bran particles (indicated as a solid black particle at 162 in Fig. 3) may be considered for purposes of theoretical discussion. As the particle passes the step edge 94, it is of course subject to the downward influence of gravity as indicated generally by the arrow 164. The electrostatic field at this point, which is in general perpendicular to the plane of the electrodes, will exert an attractive force on the particle indicated by the arrow 166. A portion of the force of electrostatic attraction will tend to act vertically in opposition to the downward pull of gravity.

Another component of this electrostatic force may be exerted horizontally in the direction of feed to urge the particle to the right in the figure. At the same time the momentum which the particle has acquired in its movement down the lower electrode also tends to move the particle to the right. The sum of these forces tending to move the particle to the right is indicated generally by the arrow 168. The particle 162 will accordingly be subjected to a resultant force whose direction and magnitude depend on the direction and magnitude of the individual forces just mentioned. In some cases this resultant force will be in the general direction indicated by arrow 170 and will be sufficient to project the particle along the path of arrow 172 through one of the spaces 80 in the upper electrode. In other cases, the resultant force applied to the particle will be insufficient to cause such attraction and projection. If the electrostatic field has been adjusted so as to attract substantially pure bran particles, then those particles which include portions of both bran and endosperm (as indicated by the half shaded circles in Fig. 3) will tend to be drawn more to the top of the layer of material passing through the field but will not be actually projected through the upper electrode.

The preliminary stratification resulting from the downward feeding of the material over the corrugations and steps in the presence of the electrostatic field and under the influence of the vibrations applied to the supporting electrode 50 present the material to the diverging electrostatic field at the end of the electrodes in a condition in which the electrostatic field of diminishing intensity at the end of the electrodes is enabled to achieve a further separation of the material. Thus, in the case of wheat stock, the relatively pure endosperm particles drop straight downwardly from the discharge edge 98 and are relatively unaffected by the field at this point. These particles are collected in receptacle 106. At the same time particles which include portions of both bran and endosperm tend to be projected outwardly in the direction of feed of the material so that they clear the divider 108 and are led by chute 110 to the intermediate receptacle 134. By

suitable adjustment of the divider 108 both longitudinally in the direction of feed and also perpendicularly to the general plane of the electrodes, the operator may control the nature and degree of the separation to a considerable extent.

The separation which takes place at this point in the present apparatus is believed to be particularly surprising because the fraction dropping directly from the discharge edge includes the heavier particles of the mixture which would normally be projected farthest to the right if the momentum and mass of the particles alone were to be considered.

While I do not wish to be bound by any particular theory as to the causes of this additional separation, it is my belief that the repeated rippling of the stock over the steps through a relatively long path of feeding, in combination with the reciprocating motion of the steps, causes a mechanical lifting of the bran or lighter particles while the heavier endosperm particles hug the steps very closely. In addition, there is an electrical lifting or stratification which may result from passing the material over a series of corrugations or steps at the edge of each of which the electrostatic field is somewhat more intense than at other points in the path. Thus the steps contribute both mechanically and electrically to the stratification of the material and to the acquisition of a substantially complete charge by each particle. It may be that the total charges acquired by the respective particles depend to some extent on the rate of acquisition of the charges and this in turn may be affected by the passage through the electrostatic field and through repeated areas of more intense field strength.

Furthermore, the separation which is obtained at the end of the electrodes appears to depend to some extent on the diverging electrostatic field and on the more horizontal orientation of the field at this point, as well as on the fact that the upper electrode extends a substantial distance beyond the lower electrode. The provision of the longitudinal slots 68 in the upper electrode permits adjustment of the upper electrode longitudinally with respect to the lower electrode and therefore permits adjustment of the extent of this overlap or projection of the upper electrode at the lower end of the machine.

While I have described the electrodes as parallel, it is possible to incline the plates slightly with respect to each other in the longitudinal direction of feed, so that the material passes through a field of increasing or diminishing intensity as may be required by the particular problem encountered. The use of the term "substantially parallel" in the claims is intended to include such minor angular variations.

In practice, my invention has been found most satisfactory in the handling of comminuted wheat stocks which have not been too finely ground. In other words, the separator may be used as a middlings purifier and will operate satisfactorily on the sizings, the coarse and fine first middlings and other middlings stock as distinguished from the finely powdered stocks wherein the particle size more nearly approaches that of the finished flour. Such dust-like or fine flour particles tend to form agglomerates which are not readily broken up and which therefore prevent the more precise separations, which are possible with sizing and middlings stocks.

The apparatus described above accomplishes

the objects of the present invention and provides a useful and accurate device for purification of stocks in the flour milling field and also in other fields where precise separation is required, and particularly where the particles of material to be separated are all relatively non-conducting.

Certain features shown but not claimed in the present application are claimed in the copending application of William A. Brastad and Eli C. Gear, Serial No. 108,476, filed August 4, 1949.

Since minor variations and changes in the exact details of construction will be apparent to persons skilled in this field, it is intended that this invention shall cover all such changes and modifications as fall within the spirit and scope of the attached claims.

Now, therefore, I claim:

1. An electrostatic separator comprising substantially parallel inclined upper and lower electrodes, the upper electrode having a plurality of openings therein through which material attracted from the lower electrode may be projected onto the upper surface of the upper electrode and the lower electrode having on its upper surface a series of transverse steps down which the material to be separated may be fed, means for feeding a thin uniform stream of the material down across said steps between the electrodes, means for maintaining a difference of potential between the electrodes, and means for collecting separately the material discharged from the respective electrodes.

2. An electrostatic separator comprising substantially parallel inclined upper and lower electrodes, the upper electrode having a plurality of openings therein through which the material attracted from the lower electrode may be projected onto the upper surface of the upper electrode and the lower electrode having on its upper surface a series of transverse steps down which the material to be separated may be fed, means for feeding a thin uniform stream of the material down across said steps between the electrodes, means for adjusting the perpendicular distance between the electrodes, and means for adjusting the relative position of the electrodes in the direction of feed, and thereby adjusting the relative orientation of said openings and steps.

3. An electrostatic separator comprising substantially parallel inclined upper and lower electrically conducting electrodes, the upper electrode having a plurality of openings therein through which material attracted from the lower electrode may be projected onto the upper surface of the upper electrode and the lower electrode having on its upper surface a series of transverse steps down which the material to be separated may be fed, means for feeding a thin uniform stream of the material down across said steps between the electrodes, the lower electrode having an extension at its lower end diverging downwardly and providing an extended electrostatic field which is more nearly horizontal than the field between the main portions of the electrodes.

4. An electrostatic separator according to claim 3 having a divider mounted at the lower end of the electrodes, and means for adjustment of the divider both longitudinally of and perpendicularly to the plane of the electrodes.

5. An electrostatic separator comprising substantially parallel inclined upper and lower metallic electrodes, the upper electrode having a plurality of downwardly inclined transverse strips

overlapping each other in stepwise formation and separated by transverse openings through which particles attracted from the lower electrode may be projected onto the upper surfaces of the strips and the lower electrode having on its upper surface a relatively large number of transversely extending corrugations down which the material to be separated may be fed and means for feeding a thin uniform stream of the material down across said corrugations between the electrodes.

6. An electrostatic separator comprising substantially parallel inclined upper and lower electrically conducting electrodes, the upper electrode having a plurality of openings therein through which material attracted from the lower electrode may be projected onto the upper surface of the upper electrode and the lower electrode having on its upper surface a series of transverse steps down which the material to be separated may be fed, and means for rapidly vibrating the lower electrode as the material is fed along it.

7. An electrostatic separator according to claim 6 having means for rapidly vibrating both the upper and lower electrodes.

8. An electrostatic separator according to claim 6 in which the electrodes are generally inclined at an angle between 30° and 35° with respect to the horizontal, and in which the individual steps of the lower electrode are inclined downwardly at an angle between 5° and 10°.

9. An electrostatic separator according to claim 6 in which the vibration is in a direction having a component substantially perpendicular to the plane of the electrode.

10. An electrostatic separator according to claim 6 in which the vibration is in a direction substantially parallel to the edges of the transverse steps.

11. An electrostatic separator comprising substantially parallel upper and lower electrodes inclined downwardly in the direction of feed, each electrode comprising a series of overlapping steps separated by substantially perpendicular risers, the risers of the upper electrode having openings therein through which particles attracted from the lower electrode may be projected onto the upper surface of the upper electrode, and means for feeding a thin uniform stream of material down across the steps of the lower electrode and between the electrodes.

12. An electrostatic separator comprising substantially parallel upper and lower electrodes inclined downwardly in the direction of feed, each electrode comprising a series of corrugations having substantially horizontal and vertical portions, the vertical portions of the upper electrode having openings therein through which particles attracted from the lower electrode may be projected onto the upper surface of the upper electrode, and means for feeding a thin uniform stream of material down across the corrugations of the lower electrode and between the electrodes.

13. An electrostatic separator comprising substantially parallel inclined upper and lower electrodes each of which comprises a series of downwardly inclined steps separated by risers, the risers of the upper electrode having openings therein through which material attracted from the lower electrode may be projected onto the upper surface of the upper electrode, and means for feeding a thin uniform stream of material down across the steps of the lower electrode and between the electrodes.

14. An electrostatic separator according to

claim 13 in which the upper and lower electrodes have the same number of steps per unit length.

15. An electrostatic separator according to claim 13 in which the upper and lower electrodes have different numbers of steps per unit length.

16. An electrostatic separator according to claim 15 in which the lower electrode has more steps per unit length than the upper electrode.

17. An electrostatic separator comprising substantially parallel inclined upper and lower electrically conducting electrodes, the upper electrode having a plurality of openings therein through which material attracted from the lower electrode may be projected onto the upper surface of the upper electrode and the lower electrode having on its upper surface a series of transverse steps down which the material to be separated may be fed, the individual steps being inclined downwardly at an angle substantially less than that at which some portions of the material to be separated just begin to move under the influence of gravity, and means for rapidly vibrating the lower electrode and thereby feeding the material down across said steps.

18. An electrostatic middlings purifier comprising substantially parallel inclined upper and lower electrodes each of which comprises a series of downwardly inclined steps, the steps of the upper electrode being separated by openings through which a first portion of material attracted from the lower electrode may be projected onto the upper surface of the upper electrode, a divider at the lower end of the electrodes having an effective separating edge parallel to the plane of the electrodes and positioned in the path of material discharged from the field between the electrodes to separate the remaining material into upper and lower second and third portions respectively, means for feeding a thin uniform stream of the material down across the steps of the lower electrode and between the electrodes, and means for collecting separately the first, second and third portions.

19. An electrostatic middlings purifier according to claim 18 in which the divider comprises an inclined plate, a transverse shaft parallel to the edges of the steps and on which the plate is supported, and means for angular adjustment of the plate with respect to the axis of the shaft.

20. An electrostatic middlings purifier comprising substantially parallel inclined upper and lower electrically conducting electrodes, the upper electrode having a plurality of openings therein through which material attracted from the low-

er electrode may be projected onto the upper surface of the upper electrode and the lower electrode having on its upper surface a series of transverse steps down which the material to be separated may be fed, and means for feeding a thin uniform stream of the material down across the steps of the lower electrode and between the electrodes.

21. An electrostatic middlings purifier comprising a frame, a first set of substantially parallel inclined upper and lower electrodes mounted in the frame, a second set of similar electrodes mounted below the first set, the upper electrode of each set having openings through which material attracted from the lower electrode of the set may be projected onto the upper surface of the upper electrode, and the lower electrode of each set having on its upper surface a series of transverse steps down which material to be separated may be fed, means for feeding a thin uniform stream of the material down across the steps of the lower electrode of the first set, means for collecting separately the portions of material discharged by the upper electrodes, a divider at the lower end of each set of electrodes for dividing the remaining material into upper and lower fractions, means for feeding the lower fraction from the first electrode in a thin uniform stream down across the steps of the lower electrode of the second pair of electrodes, and means for collecting separately the upper fraction of the first set of electrodes and the upper and lower fractions of the second set of electrodes.

22. A middlings purifier according to claim 21 in which said feeding means includes means for rapidly vibrating the frame.

23. A middlings purifier according to claim 21 in which the two sets of electrodes are substantially parallel, resilient means supporting the frame for movement in a direction parallel to the edges of the steps, and said feeding means including means for rapidly vibrating the frame back and forth in said direction.

CREIGHTON H. MORRISON.
